J. G. BENTLEY,
THREAD AND METHOD OF MAKING THE SAME,
APPLICATION FILED JAN. 10, 1921.

Patented Apr. 11, 1922.

WITNESS

Wm. D. Bell.

INVENTOR,
John G. Bentley,
BY
John Edward
ATTORNEY

UNITED STATES PATENT OFFICE.

JOHN G. BENTLEY, OF PATERSON, NEW JERSEY.

THREAD AND METHOD OF MAKING THE SAME.

1,412,446.

Specification of Letters Patent. Patented Apr. 11, 1922.

Application filed January 10, 1921. Serial No. 436,075.

To all whom it may concern:

Be it known that I, JOHN G. BENTLEY, a citizen of the United States, residing at Paterson, in the county of Passaic and State 5 of New Jersey, have invented certain new and useful Improvements in Threads and Methods of Making the Same, of which the following is a specification.

It is the principal object of this invention 10 to provide a yarn which will have superficially certain qualities that characterize yarns made of one class of fibres, as the surface feel and appearance of silk, but inherently will have qualities that characterize 15 yarns made of another class of fibres, as the elastic compressibility of wool. To state the principal object which I have especially in mind, it is to provide a thread or yarn from which to manufacture fabric suitable 20 for use in men's suitings, for example, and which fabric will have the surface feel and appearance of silk, but the texture, life and body characteristic of wool.

According to my invention, I first prepare 25 yarn to compose the warp or weft or other constituent threads of the fabric (I shall hereinafter term it "thread") which is constituted by a wool core yarn and a less compressible silk yarn wrapping spirally 30 embracing the core yarn and holding the core yarn compressed. The thread thus composed is then according to my invention made up into fabric by any fabric making process, as weaving, knitting, etc. On account 35 of the elastic compressibility of the core yarn when the covering yarn is wrapped about it and consequently constricts it by compressing its elastic fibres a hold on the wrapping or covering yarn is obtained by the core yarn which keeps the former from slipping, which is obviously a very important quality for the thread to have in order for it to be worked up successfully into a fabric and which could not 40 be obtained otherwise than by twisting the two yarns together, which would necessarily bring the core yarn to the surface of the thread so that the latter would cease to be one whose appearance and feel simulated that of the silk or other selected covering or wrapping yarn; and on account of the less compressibility of the wrapping yarn the improved 45 thread and fabric, while soft and yielding under pressure, have the surface feel and

appearance of smooth-surface materials like silk.

My invention consists, first, in thread constituted by wool core yarn and a less compressible silk yarn wrapping spirally embracing and preferably covering the core 60 yarn and holding the same compressed; and, second, in a method of forming thread whereby one or more yarns will be wrapped around another.

In the drawing,

Figure 1 is a plan view of a fragment of a fabric embodying my invention, the view being enlarged;

Figure 2 shows, enlarged, a fragment of 70 the thread composing the fabric, the wrapping or covering yarn being partially removed;

Figure 3 shows, enlarged, a fragment of 75 the core yarn at one stage in the method of forming the thread; and

Figures 4 and 5 are diagrammatic views illustrating the making of the thread.

To produce the thread of my invention I first prepare a wound package *a* of doubled 80 wool (as worsted) and silk yarns in which the wool yarn *1* stands stretched to greater extent than the silk yarn *2*; the drawing shows, simply by way of example, one wool yarn and three silk yarns. In Figure 4 a 85 weighted friction brake *b* is shown applied to the whirl *c* on the supply bobbin *d* of the wool yarn, whereas the bobbins *e* for the silk yarn have no such braking or tension-producing medium, wherefore the wool 90 yarn will be wound onto bobbin *a* stretched to greater degree than the silk yarns. By "stretched" herein I mean that it is distended, bringing its elasticity into play.

Having prepared such a package *a* of 95 doubled wool and silk yarns, the package is placed on a spinning spindle *f* (Figure 5) equipped with means to rotate it, as a whirl *g* and a suitably driven belt *h*, and also equipped with a flier *i* freely revoluble relatively to the package *a* and having a lateral guiding eye *i'* and an axial guiding eye *i''* through which the yarns extend, as shown, and the yarns are drawn from the package *a*, as by being wound up on the suitably rotated bobbin *j*, and spun. In the transfer from package *a* to bobbin *j* the wool 100 yarn, existing in package *a* stretched to greater extent than the silk yarn, now undergoes liberation and so contracts in length; 105 110

the silk yarn, however, being not stretched, or at least less stretched, undergoes no such contraction at this time. Consequently during the spinning, while the tauter wool yarn, 5 tending to adhere to a straight line between i'' and j , preserves a relatively axial or central position, the silk yarn, being of greater effective length, tends to balloon outwardly relatively to the wool yarn, and so 10 becomes wrapped around it. (So far as I know, this method of forming a thread having a core yarn which is straight and the spiralling confined to another yarn which becomes a wrapping yarn in the finished product, such method depending on 15 first doubling yarns under a condition of disparity of stretch and then spinning them while simultaneously allowing the more stretched yarn to contract, is in itself broadly new). Of course the mere wrapping 20 of the silk yarn around the wool yarn, by causing a constriction of the latter, in itself sets up a grip between the core and the wrapping tending to prevent the latter from 25 slipping on the former in the finished product. But the grip is further enhanced because at the time the wrapping occurs the wool yarn has not contracted in length to its normal limit (indeed, this may not occur 30 until the thread is later on removed from the bobbin j), or, which is the same thing, it has not expanded in diameter to its normal limit, so that ultimately it comes to exert an outward pressure on the 35 wrapping. Figure 3 illustrates a wool yarn under tension, or as it would be on bobbin

a , and Figure 2, at the right, shows the (uncovered) wool yarn relaxed or contracted to its normal length, the diameter of the yarn in the former case being less than in 40 the latter because of the known tendency of the fibres to assume true parallelism when the yarn is stretched.

Having prepared thread by the above or any other method so long as such thread 45 is constituted by an elastic compressible core yarn and a less compressible yarn wrapped about the core yarn and holding the core yarn compressed, I make the same up into a fabric, in any way, as the woven fabric 50 shown in Figure 1.

Having thus fully described my invention, what I claim as new and desire to secure by Letters Patent is:—

1. Thread comprising wool core yarn and 55 a less compressible silk yarn wrapping spirally embracing the core yarn and holding the latter compressed.
2. The method of forming thread which consists in winding yarns in doubled state 60 into a wound package with one stretched to greater extent than the other or others, and then rotating said package and meanwhile withdrawing lengthwise the doubled yarns from the package and at that time allowing the first named yarn to contract in length, whereby to spin the yarns by wrapping said other yarn or yarns around the first-named yarn.

In testimony whereof I affix my signature. 70

JOHN G. BENTLEY.
